DESIGN FOR A MEAT BLOCK SCRAPER

William J. Eck, Toledo, Ohio

Application November 9, 1939, Serial No. 88,156

Term of patent 3½ years

To all whom it may concern:

Be it known that I, William J. Eck, a citizen of the United States, residing at Toledo, in the county of Lucas, State of Ohio, United States of America, have invented a new, original, and ornamental Design for a Meat Block Scraper, of which the following is a specification, reference being had to the accompanying drawing, forming part thereof.

Figure 1 is a top plan view of the meat block scraper illustrating my new design;

Figure 2 is a side elevational view of the meat block scraper;

Figure 3 is a bottom plan view of the meat block scraper; and

Figure 4 is a fragmentary sectional view taken substantially on the line 4—4 of Figure 3.

The dominant features of my design reside in the portions shown in solid lines.

I claim:

The ornamental design for a meat block scraper, substantially as shown and described.

WILLIAM J. ECK.
